DESIGN FOR A CARTON

Raymond Guerlain, Paris, France, assignor to
Guerlain Perfumery Corporation of Delaware,
Wilmington, Del., a corporation of Delaware

Application June 12, 1937, Serial No. 69,811

Term of patent 14 years

To all whom it may concern:

Be it known that I, Raymond Guerlain, a citizen of the Republic of France, residing at Paris, France, have invented a new, original, and ornamental Design for a Carton of which the following is a specification, reference being had to the accompanying drawing forming a part thereof.

In the drawing:

Fig. 1 is a front perspective view of a carton showing my design.

Fig. 2 is a front perspective view of the top portion of the carton removed from the base.

Fig. 3 is a top perspective view of the base of the carton.

The salient feature of my design is the angular base surmounted by an annular member fitting the inside of the base of the octagonal member forming the body of the carton.

I claim:

The ornamental design for a carton substantially as shown and described.

RAYMOND GUERLAIN.
